ADJUSTABLE NEEDLE GUIDE FOR SEWING MACHINES

Andrew B. Clayton, Sea Bright, N. J., assignor to
The Singer Manufacturing Company, Elizabeth,
N. J., a corporation of New Jersey

Application December 27, 1946, Serial No. 718,705

5 Claims. (Cl. 112—227)

1

This invention relates to sewing machines and more particularly to chain stitch sewing machines having a needle guide that can be adjusted in a plurality of directions, preferably transversely, vertically, and longitudinally of the sewing machine bed.

An object of the present invention is to provide a sewing machine having an improved adjustable needle guide.

Another object of the invention is to provide an improved mounting for a needle guide which is especially adapted for use with a chain stitch sewing machine but which may also be used with other types of sewing machines.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings which form a part of this specification:

Fig. 1 is a vertical, longitudinal sectional view of a portion of a chain stitch sewing machine to which the mechanism of this invention has been applied;

Fig. 2 is a left end fragmentary view of the mechanism shown in Fig. 1;

Fig. 3 is a perspective view of a needle guide embodying the invention; and

Fig. 4 is an exploded perspective view showing parts of the needle-guide mechanism.

For purposes of illustration, the invention is shown as applied to a sewing machine having an operating mechanism of the same general construction as that shown and described in my United States Patent No. 2,345,327, dated March 28, 1944. However only as much of the machine is included herein as is necessary to an understanding of the present invention.

The sewing machine comprises a work supporting bed-plate 10 carried by a table top (not shown). Supported from the lower face of the bed-plate are a plurality of mechanisms most of which are fully described in my United States Patent No. 2,441,931, May 18, 1948. These mechanisms are enclosed by a base-housing, not herein shown, but which is well known to those versed in the art.

The sewing machine mechanism includes a rotary drive shaft 11 incorporating a crank 12 and an eccentric 13 by which, respectively, the

requisite endwise reciprocatory or loop-seizing and -shedding movements and vibratory or so-called needle avoiding movements are imparted to a pair of loopers 14 and 14'. Each looper is mounted on its own looper-carrier 16 and 16', and the looper-carriers, in turn, are supported on a looper-carrier support 15.

As previously indicated, endwise reciprocatory movement is imparted to the loopers by the crank 12, which controls this movement of the loopers through the medium of a pitman 17, rock arms 18 and 19 journaled on a stud 21 and through a link 22 connecting the rocker arm 19 with the looper-carrier 16. The second looper-carrier 16' is connected to the first looper-carrier 16 by a link 23, thereby causing the two looper-carriers to rock in unison and their loopers 14, 14' to reciprocate in synchronism.

The sidewise or laterally vibrating movements of the loopers are effected through the medium of an eccentric actuated fork 24 and a tubular rock shaft 26, the latter extending longitudinally of the bed-plate 10 and being journaled in bushings 27, 28 fitted within a bearing support 29. The support 29 forms a part of a branch 31 depending from the underside of the bed-plate 10 and thus the support 29 carries the rock shaft 26, the left end of which, as viewed in Fig. 1, supports a looper throw-out device designated generally by the numeral 32, and the looper throw-out device carries the looper-carrier support 15, hereinbefore mentioned.

The looper throw-out device 32 is fully described and claimed in my hereinbefore mentioned United States Patent No. 2,441,931, therefore a general description of this mechanism will suffice. The throwout device 32 has a pair of face abutting disks 33 and 34, the disk 33 being formed as an integral part of and therefore rockable with one end of the horizontally disposed looper rock shaft 26. The disk 34, and the looper-carrier support 15, carried thereby, are mounted for limited angular movement with respect to the disk 33 and thus the disk 34 and the support 15 can be swung beyond the normal rocking movement afforded them by the disk 33 and the rock shaft 26. A latch bar 36, slidably mounted in the disk 33, carries at its upper end a latch-lug 37, that is positioned to enter or be released from a complementary tapered recess 38 formed in the disk 34. The latch bar 36 by means of a spring 39 is biased to hold the lug 37 in the recess 38 and thereby normally to cause the disks 33 and 34 to operate as a unit. A spring biased arm 41, secured to a shaft

42 and operated by a lever 43 also secured to the shaft 42, is positioned to move the bar 36 and lug 37 against the biasing spring 39 and thereby to allow the disk 34 to move independently of the disk 33. The looper-carrier support 15 journals rock pins 44 and 44' the front end of each of which respectively supports the looper carriers 16 and 16'. The upper end of each looper-carrier has secured to it one of the loopers 14 and 14'. The mechanism, herein shown, also provides a four-motion lower feed mechanism comprising a feed-bar 46, a feed dog 47, a feed-drive rock shaft 48 and a feed-lift rock shaft 49. This mechanism is more fully described in my patent No. 2,441,931, mentioned above.

A pair of vertically inclined needles 51 and 51' are carried by a needle clamp 52 formed on the lower end of a needle bar 53, the latter being reciprocably mounted in an overhanging arm-head 54 of the sewing machine. The mechanism for reciprocating the needle bar 53 is of any known type and therefore need not be illustrated or described. Both of the needles 51 and 51' are guided in their downward movements by a pair of adjustably mounted needle guides 56 and 56' having beveled upper ends. The needle guides are supported from the bearing support 29 by means of a split collar 57 that is adjustably held in place on the said bearing support by a clamping screw 58. The collar 57 has an upwardly extending arm 59, grooved as at 61 to accommodate a bar 62 extending horizontally crosswise of the line of feed and held in said groove by a screw 63 passing through a hole (not shown) in the bar 62 and threaded into the arm 59. The bar 62, which is preferably rectangular in cross section, is provided with two horizontally extending rectangular slots 64 and 64' spaced in such a manner that the horizontal distance between the centers of the two holes is approximately equal to the horizontal distance between the two needles 51 and 51'.

At each of the holes 64 and 64', the bar 62 carries a slide 66, which supports the needle guides 56 and 56' respectively. Since the means for supporting both needle guides is identical, only one will be described. Slide 66 has a pair of grooves 67 and 68, the former groove 67 being formed horizontally in a rear portion of the slide and being arranged to fit over the bar 62, whereas the latter groove 68 is formed vertically in a forward portion of the slide and accommodates the lower substantially vertically positioned support leg 69' of the needle guide 56'. The support leg 69' has a vertically elongated slot 71 and each slide 66 has a horizontal bore 72. The needle guide and slide are held to the bar 62 by a bolt 73 that passes through the slot 71, through the bore 72, through the slot 64' and at its rear is threaded into a nut 74. The front surface of the nut 74 carries a raised neck portion 75 which enters the slot 64', thereby providing wrench-action to keep the nut from turning when a screw driver is used to turn the slotted head portion of the bolt 73. It will be noted that the upper end of the needle guide 56' is forwardly offset to a greater extent than a forwardly offset portion of the guide 56. This is because of the position of the needles 51 and 51', one being slightly ahead of the other.

The beveled faces of the needle guides 56 and 56' can simultaneously be adjusted toward or away from the back of the needle, which direction is also transversely of the sewing machine bed, by loosening the clamp screw 58 and slightly

rotating the split collar 57 on the support 29. Either needle guide can be adjusted vertically by loosening the bolt 73 and sliding the needle guide up and down as desired. Either needle guide can be adjusted longitudinally of the sewing machine bed by loosening the bolt 73 and moving the slide horizontally on the bar 62, allowing the bolt 73 to move sidewise in the slot 64' or 64, whichever is involved.

10 Having thus set forth the nature of the invention, what I claim herein is:

1. In a sewing machine having a bearing support, a needle guide mechanism comprising a split collar clamped to said bearing support, an

15 arm extending vertically from said collar, a horizontally extending bar secured to said arm, said bar having a rectangular slot provided therein, a slide carried by said bar in the region of said rectangular slot, a needle guide having a slot 20 and being carried by said slide, and a bolt for adjustably securing said needle-guide and said slide to said bar.

2. In a sewing machine having a bearing support, a needle guide mechanism comprising a split collar clamped to said bearing support, an upwardly extending arm formed integral with said collar and provided with a horizontally extending groove, a horizontally extending support bar fitted into said groove and secured to said

30 arm, said bar having a plurality of horizontally extending slots, a slide carried by said bar in the region of each of said slots and each of said slides having two grooves, one of said grooves being engaged by said support bar, an apertured 35 needle guide carried by the other groove of each of said slides, and a bolt for adjustably securing each needle-guide and slide to said bar.

3. In a sewing machine, a work-support, work-feeding mechanism, and stitch-forming mechanism

40 including a plurality of needles spaced from each other crosswise of the line of feed, in combination, an arm disposed below said work-support to extend crosswise of the line of feed and provided with a plurality of horizontally elongated and aligned slots, a plurality of needle-guides each of which is provided with a slot formed longitudinally of said needle-guide, means for individually securing said needle-guides upon said arm by securing means passing through the 45 slots of said needle-guides and through the respective said slots of the arm and thereby providing for horizontal and vertical adjustments of said needle-guides, a bearing support, and mounting means upon said support providing for 50 adjustment of said arm angularly about said support.

4. In a chain stitch sewing machine having a sewing machine bed, a needle-guide mechanism supported from said bed and comprising a horizontally extending bar provided with a slot, a slide carried by said bar in the region of said slot, said slide having transverse grooves on opposite sides thereof, a needle-guide having a vertically disposed support leg provided with a vertically extending slot and engaging one of the grooves in said slide, the other of said grooves in said slide being engaged by said bar, and a bolt for adjustably securing said vertically disposed support leg of said needle-guide and said 70 slide to said bar.

5. A needle-guide for sewing machines, comprising, a horizontally extending bar having a horizontally extending slot, a slide having transverse grooves, one of said grooves being engaged 75 by said bar in the region of said slot, a needle-

guide having a vertically disposed leg provided with a vertically extending slot and engaging the other groove of said slide, and a means for adjustably securing said needle-guide and said slide to said bar.
